FIG. 1

FIG. 4

FIG. 1 is a perspective view of a plaque for support of a work of art showing my new design, as viewed at a 45° angle to the plane of the drawing;

FIG. 2 is a rear elevational view thereof;

FIG. 3 is a side elevational view thereof, as seen from the left side of FIG. 2; and

FIG. 4 is a top view thereof, as seen from the top of FIG. 2.

I claim:

The ornamental design for a plaque for support of a work of art, substantially as shown and described.
